STAMP INKING APPARATUS

George E. Ryckman, Edgewood, Pa., assignor to
Miller Pottery Engineering Company, Swiss-
vale, Pa., a corporation of Pennsylvania

Application July 8, 1950, Serial No. 172,747

3 Claims. (Cl. 101—351)

1

This invention relates to apparatus for inking stamps that decorate dinnerware and other articles, and more particularly to inking apparatus for use with the decorating machine shown in my copending patent application, Serial No. 169,356, filed June 21, 1950, now Patent No. 2,612,106.

It is among the objects of this invention to provide inking apparatus in which the ink is spread evenly over the inking roller, in which the supply of ink to the inking roller can be closely controlled, in which the supply of ink to the inking roller can be stopped without stopping rotation of the roller, and in which the inking roller is mounted to swing from an operating position to a non-operating position.

The preferred embodiment of the invention is illustrated in the accompanying drawings in which Fig. 1 is a side view, partly in vertical section, showing the inking apparatus in operating position relative to a decoration stamping machine; Fig. 2 is a horizontal section taken on the line II—II of Fig. 1; Fig. 3 is an enlarged plan view of the apparatus; Fig. 4 is a cross section taken on the line IV—IV of Fig. 3; Fig. 5 is a fragmentary vertical section taken on the line V—V of Fig. 3; Fig. 6 is a view of the inner end of the apparatus; Figs. 7 and 8 are cross sections taken on the lines VII—VII and VIII—VIII respectively, of Fig. 3; Fig. 9 is a fragmentary horizontal section taken on the line IX—IX of Fig. 7 and Fig. 10 is a fragmentary section taken on the line X—X of Fig. 7.

Referring to Fig. 1 of the drawings, the continuously rotating table 1 of a dinnerware decorating machine like that shown in my above mentioned copending patent application is mounted on the continuously rotating center shaft 2 of the machine. Extending radially away from the lower end of this shaft is a leg 3, on the outer end of which a box 4 is mounted. Rigidly mounted on top of this box is a hollow vertical post 6 that supports a bearing 7 at its upper end. A tube 8 is rigidly mounted in this bearing and extends down through the post and through a circular opening in the top of the box. The tube can be turned in the post for a purpose to be explained later, but its rotation is limited to about 90° by means of stops 9 projecting from it inside the post. These stops will engage a bushing 11 mounted in the side of the post, in which a hand screw 12 is threaded. The inner end of the screw is pointed so that it can project into either one of two recesses 13 in the side of the tube beside the stops 9 for locking

the tube in either of two positions about 90° apart.

Ball bearings 14 are mounted in the opposite ends of the tube to support a vertical drive shaft 16 that extends above and below them. This shaft is driven from its lower end by a chain 17 and sprocket 18 which are driven from the main drive of the machine (not shown). The upper end of tube 8 extends through a long horizontal bed plate 19 that is rigidly mounted on bearing 7. This bed plate supports the rollers by which ink is transferred from a well or fountain to the decorating stamps that are carried by the machine.

The largest one of these rollers is the metal inking roller 21, shown in Figs. 1, 3, 6 and 7, which the stamps 22 pass over as they are carried around the machine. When the inking roller is in operating position as shown, its axis is radial of the machine table. The inking roller is rigidly mounted on a horizontal shaft 23, the inner or machine end of which is journaled in a bearing 24 supported by the inner end of bed plate 19. The other end of the shaft extends outward through spaced bearings 26 and 27 supported from the plate and into a bearing 28 supported by a bracket 29 also mounted on the plate. The inking roller shaft is driven continuously by vertical drive shaft 16 through bevel gears 31 and 32 mounted on the two shafts. Preferably, the linear speed of the inking roller is the same as the linear speed of the centers of the stamps as they travel around the center shaft 2.

Disposed at one side of the inking roller is a U-shape frame 34 in which two vertically spaced backing rollers 35 and 36 are journaled in parallel relation. These rollers are made of metal. The bottom of the frame is pivotally supported by horizontal pivot pins 37 supported by the bed plate, whereby the frame can be swung toward the inking roller by means of coil springs 38 that connect its upper ends to the upper ends of a pair of arms 39 on the opposite side of the inking roller shaft. The lower ends of these arms are rigidly connected by a horizontal bar 41 and are pivotally supported by pivots 42 mounted on the bed plate. The center of the bar has an outwardly projecting bifurcated lug 43 that straddles screw 44 rigidly mounted in the bed plate. A large nut 45 is threaded on the upper end of this screw and presses down on the lug. By adjusting the nut up and down, arms 39 can be swung toward and away from the inking roller shaft to vary the tension on the coil springs.

A spreading roller 47, made of rubber or simi-

lar resilient material, is disposed between and in engagement with the inking roller and the two backing rollers. That is, the spring-biased backing rollers press the spreading roller against the side of the inking roller. The spreading roller is considerably longer than the other rollers and has its outer end connected by a universal joint to one end of a link 48, the opposite end of which is connected by a universal joint to a stub shaft 49 rotatably mounted in a bracket 51. The stub shaft cannot be moved axially relative to the bracket, but must move with the bracket. The link 48 extends through a horizontal tube 52 that is connected at one end to a plate 53 fastened to the bracket. This tube prevents the link from dropping down when it is disconnected from the spreading roller.

The bracket 51 is joined to a yoke 55 that has its opposite sides supported and guided by two pairs of horizontal rollers 56 and one pair of vertical rollers 57, all supported from the bed plate, so that the yoke can be reciprocated lengthwise of the plate without moving vertically or sidewise. The opposite sides of the yoke are connected by a central portion provided with a transverse slot 58. Fitted in this slot is a roller 59 which is carried by one end of an arm 61, the opposite end of which is attached to a worm gear 62 mounted on the lower end of a short vertical shaft 63 journaled in the bracket 29 above it, as shown in Figs. 3, 4 and 5. The gear is rotated continuously by a worm 64 mounted on the inking roller shaft 23 beside it. Consequently, as the gears revolve, roller 59 moves back and forth in the yoke slot and thereby reciprocates the yoke. This motion is transmitted through bracket 51 and link 48 to spreading roller 47, which therefore is slid back and forth between the horizontal rollers that support it. At the same time, the spreading roller is rotated continuously by frictional contact with the driven inking roller, and the spreading roller in turn rotates the backing rollers continuously.

Spaced behind the lower backing roller 35 is a parallel fountain roller 66, the ends of which are journaled in upright bearing blocks 67 mounted on the bed plate. The fountain roller is made of metal. The upper portions of the bearing blocks are connected behind the fountain roller by a heavy bar 68 that has a lower edge close to the roller from which the bar is inclined upward and away. A doctor blade 69 engages the inner face of this bar and has its upper edge attached to it by screws 71. The lower edge of the blade extends along the fountain roller very close to it, and can be pressed against the roller with uniform pressure by means of closely spaced set screws 72 mounted in the bar. In the space between the bar and the fountain roller at the opposite ends of the roller there are triangular sealing members 73, so that a trough or well or fountain is formed between them for receiving a supply of ink. By "ink" is meant any decorating fluid that it may be desired to use, such as ceramic colors.

It will be seen that if the fountain roller is rotated in a clockwise direction as viewed in Fig. 7, it will draw ink out of the bottom of the fountain on its surface. The thickness of the film of ink adhering to the roller is controlled by adjusting the set screws 72 engaging the doctor blade. To further control the rate at which ink is removed by the fountain roller from the fountain, the roller preferably is rotated intermittently. For this purpose the outer end of

the roller projects from the outer bearing block 67 and has a clutch plate 75 oscillatably mounted on it as shown in Figs. 3 and 8. One end of a coil spring clutch 76 is attached to this plate, the rest of the spring tightly encircling the projecting end of the roller. When the clutch plate is swung in a counterclockwise direction as viewed in Fig. 8, the spring will tighten still more around the roller and turn it. When the plate is swung in the opposite direction, the coils of the spring clutch will expand and slip on the roller without turning it. A similar coil spring clutch 77 on the projecting opposite end of the fountain roller helps prevent reverse rotation of the roller by tightening itself on the roller when the other spring clutch loosens itself. The periphery of the clutch plate associated with coil spring clutch 77 is provided with a hole for receiving a bar for manually rocking the plate to test the action of the doctor blade in making an initial setup. The clutch plate 75 is oscillated by means of a link 78 that has one end pivotally connected to the top of the plate. The other end of the link is forked and pivotally connected to a nut 79 threaded on an upright screw 81 which is journaled in a lever arm 82. The arm is rigidly mounted on one end of a horizontal rocker shaft 83 whose opposite ends are journaled in bearings 84 on the bed plate. The upper end of the lever arm carries a roller 86 which engages a cam 87 mounted on the inking roller shaft. As this cam rotates, it causes the lever arm to swing back and forth to operate the fountain roller clutch. By turning screw 81, the lower end of link 78 can be adjusted up or down and therefore the throw of the clutch plate will be varied in order to vary the number of degrees that the fountain roller is turned each time clutch spring 76 grips it.

In order to hold the cam roller 86 against the cam at all times, the opposite end of rocker shaft 83 is provided with an arm 88 that extends down through a slot 89 in the bed plate as shown in Fig. 7. Below the plate this arm is pivotally connected to a rod 91 that extends laterally into a sleeve 92. Inside the sleeve there is a coil spring 93 which is compressed between the end of the rod and the opposite end of the sleeve. At the latter end of the sleeve a pointed end projects into a depression in a block 94 suspended from the bed plate. The coil spring therefore urges the arm away from the block and thus keeps the cam roller swung up against cam 87.

Due to the fact that the fountain roller rotates intermittently while the backing rollers rotate continuously at a rather high speed, it is desirable to transfer ink from the fountain roller to one of the backing rollers by an element which can engage only one roller at a time. For this purpose a transfer roller 96 is provided and is disposed in the space between the fountain roller and the lower backing roller 35. The diameter of the transfer roller is less than the distance between the two adjacent rollers so that the transfer roller cannot engage both of the other rollers at the same time. The transfer roller may be made of the same material as the spreading roller. For moving the transfer roller back and forth between the adjacent rollers, it is journaled in the opposite ends of an inverted U-shape frame 97, the top of which is pivotally supported by pivot pins 98 mounted in the backing roller frame 34. One end of the transfer roller frame projects down into bed plate slot 75 89 and is pivotally connected to the upper end

of a rod 99 that extends down through the slot. As shown in Figs. 7 and 10, the lower end of this rod extends slidably through the hollow portion of a horizontal pin 101 that is rotatably mounted in the lower end of arm 88. Inside this hollow pin there is a plunger 102 that is pressed tightly against the rod by a coil spring 103 compressed between the plunger and a screw plug 104 in the outer end of the pin. The friction between the plunger and rod is great enough so that in normal operation the oscillating arm 88 will transmit its motion through the rod to the transfer frame and thereby swing the transfer roller first into engagement with the fountain roller and then back into engagement with the 15 rotating lower backing roller.

When it becomes desirable to stop feeding ink to the inking roller, the oscillations of transfer frame 97 are stopped by swinging a stop member 106, which is pivotally mounted at 107 on the bed plate as shown in Figs. 7 and 9, into position behind the frame so that the frame cannot swing toward the fountain roller. However, the inking roller can continue to rotate and rocker shaft 83 can continue to oscillate, because hollow pin 101 can slide back and forth on rod 99.

Each decorating stamp that passes across the top of the inking roller preferably is rotatable on a vertical axis. As the stamp starts to leave the inking apparatus the forward side of the stamp will engage a horizontal bar 108 which is in its path. One end of this bar is supported by a sleeve 109 oscillatably mounted on a post 111 mounted on the bed plate. Turning of the sleeve is restrained by a coil spring 112 attached to it and to the post as shown in Fig. 8. As the stamp travels ahead its frictional engagement with the bar causes the stamp to rotate a few degrees until the end of the bar slips off the stamp and swings back to its normal position.

In order to service this apparatus the bed plate can be swung laterally to position the entire apparatus beside table 1 where it is easy to reach. This is done after hand screw 12 in post 6 has been retracted to permit tube 8 to be turned therein.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. Apparatus for inking a stamp, comprising a continuously rotating horizontal inking roller, a spreading roller extending along the inking roller in engagement with it, a backing roller engaging the spreading roller, a fountain roller spaced from the backing roller, a doctor blade extending along one side of the fountain roller with its lower edge close to that roller to form an ink-receiving well

between them, a transfer roller journaled between the fountain roller and backing roller, rocker means, means connected to said rocker means and actuated thereby for intermittently rotating the fountain roller, means connected to said rocker means for moving the transfer roller back and forth between the fountain roller and backing roller and including a yielding friction connection, means for adjusting the friction in said connection to vary the pressure of the transfer roller against the fountain and backing rollers and a manually operable member for stopping said movement of the transfer roller while the rocker means continues to rock.

2. Apparatus for inking a stamp, comprising a continuously rotating horizontal inking roller, a floating spreading roller extending along the inking roller, a backing roller holding the spreading roller in engagement with the inking roller, a reciprocal member, a support for said member, continuously rotating means for reciprocating said member along said support lengthwise of the rollers, means including a universal joint connecting said member with the spreading roller to reciprocate the latter, an ink fountain, and means for transferring ink from the fountain to the spreading roller.

3. Apparatus for inking a stamp, comprising a vertical hollow post mounted in fixed position, a rotatable tube extending through the post and supported thereby, a horizontal bed plate supported by the upper end of the tube, a drive shaft extending through the tube and plate, means connected to the lower end of the shaft for driving it, a horizontal shaft rotatably supported by said plate and driven by said drive shaft, an inking roller on the plate driven by said driven shaft, an ink fountain on said plate, means for transferring ink from the fountain to the inking roller and manually operable means for normally holding said tube stationary in the post but releasable to permit the tube to be turned in order to swing said plate laterally to another position.
